Ralph L. Du Bois, 6126 S. Lewis, Tulsa, Okla.

Filed May 8, 1964, Ser. No. 79,886

Term of patent 14 years

(Cl. D26—13)

Fig. 2.

Fig. 1.

Fig. 3.

A portion of the switch plate is stippled to indicate a contrast in appearance.

I claim:

The ornamental design for a switch plate, substantially as shown and described.
